ENVELOP-SEALING MACHINE.

1,120,688.

Specification of Letters Patent. Patented Dec. 15, 1914.

Application filed November 5, 1914. Serial No. 871,431.

(DEDICATED TO THE PUBLIC.)

To all whom it may concern:

Be it known that I, FRED W. CARRINGTON, a citizen of the United States, residing at Burlington, in the county of Chittenden and State of Vermont, have invented new and useful Improvements in Envelop-Sealing Machines, of which the following is a specification.

In accordance with the provisions of the act of March 3, 1883, ch. 143, 22 Stat. L. 625, it is hereby stipulated that the invention described herein may be used by the Government, or any of its officers or employees in prosecution of work for the Government, or by any other person in the United States, without the payment to me of any royalty thereon.

This invention relates to envelop sealing machines and has for its object improvements therein resulting in a machine simple in construction, efficient in operation, and which can be run at a high rate of speed without its efficiency being impaired. With this object in view, I have constructed a machine to carry out the above object, several views of said machine being illustrated in the accompanying drawing, in which—

Figure 1 is an elevation; Fig. 2 is a top plan view; Fig. 3 is a top plan on an enlarged scale of the middle part of the machine with portions thereof broken away. Fig. 4 is a view in side elevation of that part of the machine illustrated in Fig. 3. Fig. 5 is a detail.

The machine shown in the drawing comprises a suitable frame 1 carried by legs 2, the operating mechanism being carried on the frame. The unsealed envelopes are positioned at the right end of the machine in Fig. 1 and fed therethrough as they are operated upon, the sealed envelopes being stacked at the right end.

The envelopes are fed forward one at a time by the separating mechanism, which comprises an endless belt 10 passing over the pulleys 11 and 12 fixed to the shafts 13 and 14 respectively, the shaft 14 being loosely carried in the side members of the frame 2. The other shaft is positively driven and thus imparts motion to the belt 10. This belt is made of some substance such as rubber and is preferably corrugated to impart added friction to its hold

on the envelopes. The envelopes are placed directly on this belt and the lowermost of the stack moves with the belt. To properly position the envelopes on this belt, a gage is carried to one side of the belt, the belt being of a width narrower than the small size of a commercial envelop in ordinary use. This gage comprises a base member 16 and the upstanding arms 17—17 as clearly shown in Fig. 5.

To enable envelopes of various sizes to be positioned on the belt, the gage member 16 is carried on the screw threaded part 18 of the member 19 rotatably mounted on one side of the frame and carrying the crank 20 to permit of easy manual adjustment 70 thereof. To prevent the gage 16 turning with the screw 18, the guide pin 21 carried by the frame passes loosely through the member 16, on one side of the feed element 19. The rods 22—22 carried by the members 75 23—23, removably fixed to the frame, form an envelop stop on the side opposite to the gage 16. To prevent more than one envelop being fed through the machine, there is provided a separating roll 24 fixed to a shaft 25 80 supported in the spring bearings 26. This roll is positioned to revolve in close proximity to the belt 10, in fact, so close as to permit of but one envelop being passed through 85 at a time.

What has been described thus far is substantially a hopper one side wall of which is adjustable laterally, the bottom of which is formed by the belt 10 and the front wall of which is formed by the separating roll 90 24. It has been found by experience that where a large number of envelopes are placed directly on the belt 10, the weight of the envelopes exerting its full force on the belt, will tend to interfere greatly with the successful operation of the separator mechanism. To obviate this difficulty and yet permit of stacking a large number of envelopes in the hopper, the rods 22—22 are curved as shown clearly in Fig. 5. This will cause the 100 envelopes to be stacked in the hopper in a stepped arrangement, a great part of the weight thereof being carried by the rods.

As the lowermost envelop is separated from the rest of the envelopes in the hopper 105 and fed forward, it passes between the two endless belts 27 and 28, and is carried thereby part way through the machine. The up-

per belt is carried on pulleys 29 and 30, the shafts 31 and 32 of which are supported in the bearings 33. The bearings 33 are movably mounted on pins 34 and are acted upon by opposed springs 35 and 36 carried about the pins 34, the lower springs 35 being stronger than the upper springs. The lower belt 28 is carried about pulleys 37 and 38; the shafts 39 and 40 are supported in the fixed bearings 41. As a result of the yielding character of the bearings 33, the upper pulleys and the belt carried thereby are normally pressed in yielding contact with the lower pulleys and belt. The feed thus described can therefore adjust itself to envelopes of various thicknesses.

The envelopes are placed in the hopper with their longer dimension in the direction of the feed thereof, their flap edges 20 against the gage 18 and with the flap pendant. The feed belts 27 and 28 are extremely narrow, so narrow in fact that when the envelopes are fed along thereby, the flaps will be free of the belts so that the 25 flaps can be operated upon as hereinafter set out, while the envelopes are being fed along. It will be noticed also that the feed belts 27 and 28 are substantially narrower than the separator belt. The purpose 30 of this will appear hereinafter.

42 is the flap lifter and comprises a flat sheet metal plate located laterally of the feed belts and substantially on a level with the plane of the contacting surfaces thereof. One edge 43 of this flap lifter is parallel to the length of the belts and in close proximity thereto, and the other edge 44 is at an angle thereto, the two edges terminating in close proximity to each other and above 40 the separating belt 10 and to the side of the separating roll 24. At the pointed end 45 of the plate, the edge 43 is cut away as at 46 to produce the double bevel shown. The edges 44 and 46 are curved downwardly 45 and inwardly to provide rounded edges to prevent the tearing of the envelopes. The cut away part 46 in addition to being necessary to prevent the plate 42 interfering with the separating mechanism also results 50 in a separating edge which is more certain and more efficient in its separating action. It is obvious, therefore, that an envelope placed in the hopper and removed therefrom to the feeding belts by the separator 55 mechanism will have its flap raised into the plane of the front of the envelop as the envelop is fed along.

The fact that the feed belts 27 and 28 are substantially narrower than the separator belt has been commented on previously. An examination of Fig. 2 will also show that the separator roll 24 is narrower than the separator belt and is substantially of the width of the feed belts 27 and 28. As 65 a result of this construction, the tapered

end 45 of the flap lifter 42 can overlie the separator belt and thus raise the flaps of the envelop without interfering with the feed thereof. This operation is in fact started while the envelop is still in the grip of the 70 separating mechanism.

The envelop flaps are moistened by the moistening roller 47 carried by the shaft 48 within the water reservoir 49. The top of the roller is on a level with the plate 42. 75 The roller need not be of any particular character except that it must have an absorbent surface. The location of the roller is such that the flap of an envelop turned into the plane of the front thereof as described previously will pass over the moistening roller and contact therewith. To make the contact of the flap and the roller positive, the presser member 50 is provided as shown in Figs. 2 and 4, the member 50 80 being formed from the plate 42 and supported thereby by means of the neck 51. As the envelopes to be sealed may be of different sizes, some provision is advisable for enabling the moistening roller to be shifted laterally across the machine. This result is obtained in the embodiment here disclosed by mounting the roller loosely on its shaft and providing a collar 52 at one side thereof, through which is passed the 85 nut 53 for locking the moistening roller to its shaft. As an adjustment of the roller will also necessitate a corresponding adjustment of the presser member 50, the plate 42 is made adjustable laterally of the machine by having the threaded bar 54 pass through the members 55 depending from the plate. By turning the crank 56 carried by the bar, the plate 42 and the presser member 50 are both adjusted. Formed integral with the water reservoir and sloping upwardly from the top thereof in all directions is what forms substantially a funnel 157, see Fig. 4, to return to the reservoir, surplus water which may have fallen from 90 some part of the machine.

Water is supplied to the reservoir from the tank 57 carried by the frame; 58 is the filling opening, normally closed by a cap; the feed pipe 59 leads from the bottom of the tank and empties into the reservoir 49, substantially at the point shown in Fig. 1. The pipe 60 enters the tank near the top and extends into the reservoir slightly below the lower end of the pipe 59. 100 The feed from the tank to the reservoir will therefore be a barometric one, the level of the water in the reservoir being kept at substantially the level of the lower end of the pipe 60, as this level is found 105 gives the best results. Because of the fact that some gums used on the flap of envelopes are not softened quickly by cold water, it is found advisable and preferable to heat the water in the reservoir. For this 110

purpose the heater 61 is carried by a shelf 62 suspended from the frame-work beneath the reservoir by means of the upstanding ends 63 thereof engaging the depending bracket members 64 and 65. From the bracket member 64 is also suspended the catch basin or tray 66 and 67 is the faucet to drain it.

The means for turning the envelop back 10 into sealing position comprises the plate 68 pivoted to the plate 69 at 70. The turning plate 68 comprises the forward part 71, which is substantially vertical, the plate being gradually twisted as shown in the drawing 15 so that the edge of the envelop flap will first strike the part 71 of the plate 68, and will then be gradually turned into a horizontal plane as the envelop is fed along. The plate 69 is of the shape shown, the part 20 72 being substantially on a level with the contacting surfaces of the belts and well within the space between the upper and lower pulleys 30 and 37 on the left so that an envelop fed off from between the belts 25 will be fed directly onto the plate 69 and then between the sealing rollers.

To enable the flap turning plate 68 to be used with envelops of different sizes, the plate 69 is made laterally adjustable by 30 mounting it upon the threaded shaft 73 operated by the crank 74. The flaps after being turned down as described are pressed into contact with the envelop by the two sets of rollers 75, 76 and 77, 78. The upper 35 rollers 75 and 77 are mounted upon the shafts 79 and 81, carried in bearings 83 supported in the same way as are the bearings 33 described in detail previously, except that the upper springs are stronger than 40 the lower springs. The lower rolls are carried by the shafts 80 and 82 supported in the fixed bearings 84. It will be noticed that the part 72 of the plate 69 extends almost to the line where the rolls 75 and 45 76 touch, so that the envelop thus far has been supported from beneath at all points.

At the left hand end of the machine in Figs. 1 and 2 and supported from the frame as shown is the stacker, in the form of a 50 receptacle having a bottom 85 arranged at substantially an angle of 45° to the horizontal, the side walls 86 and 87 and the end-walls 88 and 89. The right hand end of the bottom 85 is bent as shown at 90, to prevent any envelops being stuck in between the bottom 85 and the end 89. Cut 55 in the sides 86 and 87 are the slots 90 and 91 two on each side. These slots are parallel to the end 88 and are arranged in the upper 60 end of the sides. Slidably carried in these slots are the lugs 92 and 93 extending laterally at each side from the end of the plate 94 curved as shown. Due to the arrangement of the slots and the pins the weighted 65 plate 94 is freely movable upwardly, but

always to positions parallel with that shown in Fig. 1. The lowermost position of the weight 94 is substantially above the top of the frame 1 and above the plane along which the envelop is fed through the machine. The sealing rollers 75, 76, 77 and 78 are intended to be operated at a great rate of speed and the envelops will be shot into the stacker with a great deal of force so that the first envelop will be caught in 75 between the bottom 85 and the weight 94. Each succeeding envelop will be fed below those already in the stacker. Because of the curvature in the plate 94, the envelops in the stacker are buckled in conformity 80 therewith. This fact coupled with the action of the weight 94 results in the completion of the sealing operation in the stacker. The sides and the bottom are cut away as at 95 and 96 to enable the envelops 85 to be lifted out of the stacker more easily.

Any mechanism for driving the machine can be employed and the one here shown consists of two electric motors 100 and 101 carried on the shelf 102 and controlled by 90 switches 103 and 104. The motor 101 drives a belt 105, which in turn rotates the pulley 106 fixed to the shaft 40. So also the motor 100 drives the shaft 32 through the intermediary of the pulley 108 carried thereby 95 and of the belt 107. The shaft 40 in addition to driving the lower belt is also the main drive shaft for the moistening roll and the separating mechanism whereas the shaft 32 drives the upper feed belt and the sealing mechanism. It will thus be seen that not only are both of the feed belts driven positively, but they are driven from diametrically opposite points. A more uniform and positive gripping and feed action of 100 the belts upon the envelops follows naturally from what might be termed the balanced drive of the feed belts.

The separator belt 10 is driven from the shaft 40 through the pulleys 109 and 110 110 fixed to the shafts 40 and 13, respectively, and the drive belt 111 passing around them. The separator pulley 24 is also driven from the shaft 40 through the pulleys 112 and 113 115 fixed to the shafts 40 and 25 and the belt 114. It will be noticed that the separator roll 24 is driven at the same rate of speed as are the pulleys carrying the feed belts 27 and 28 whereas the separator belt 10 is driven at a slower speed due to the pulley 120 110 being larger than the pulley 109.

The action of the separator roll will be to push back the envelops faster than they are fed forward with the exception of the lowermost envelop, which will be fed forward, due to the grip of the belt thereon and of the slight spacing of the roller 24 from the belt 10. Furthermore, the endless belts 27 and 28 will move at a greater speed 125 than will the belt 10. The effect will be that 130

4
as soon as an envelop is gripped between the two feed belts, its feed is increased and it is pulled out of the way of the next envelop.

- 5 The shaft 40 also drives the pulley 115 fixed to the stub shaft 111 carried by the frame through the belt 117, and the shaft 48 carrying the sealing roller 47 is in turn rotated by the stub shaft 116 through the 10 pulley 118 carried thereby and the belt 119 and the pulley 120 mounted on the shaft. The moistening roller is rotated much more slowly than is the driving mechanism thus far described.
- 15 The shaft 32 drives the shaft 81 and in turn the sealing roll 77 through the pulleys 121 and 122 fixed to the outer ends of the respective shafts and the belt 123 passing around said pulleys. The shaft 81 in turn 20 drives the shaft 79 and the roller carried thereby through the pulleys 124 and 125 fixed to the inner ends of said shaft and the belt 126 passing thereover.

In the practical operation of the machine 25 a number of envelops is placed in the hopper to rest directly upon the separator belt. The envelops are arranged one upon the other, with the flaps hanging down, the flap edge thereof toward the gage member 16. 30 To take part of the weight of the envelops from off the belt, the opposite edges thereof are pushed against the members 22, 22. The gage 16 is then adjusted as required. The flap turner plate 42, the moistening roll 47, 35 and the flap-closing members 68 and 69 are each adjusted to operate most efficiently with the particular size envelop used. The envelops in the hopper are pressed down against the belt 10 by the hand or by a 40 weight and the switches 103 and 104 turned to close the circuits to both motors.

The lowermost envelop will be separated from the rest and fed forward. The pointed end 45 of the flap opener 42 will enter 45 between the flap and the body of the envelop almost immediately upon the forward movement thereof and as this movement is continued, the flap will be turned into the plane of the envelop and as the feed continues, 50 will be forced into contact with the moistening roll and moistened. Upon the further feeding of the envelop, the flap will contact with the member 71, 68 and be turned against the body thereof. As the envelop 55 is passed between the pressing rolls, the moistened flap is pressed into close contact with the envelop and the envelop thus sealed. The envelop is then projected into the hopper and beneath the weight as described previously.

60 The machine herein described is intended as merely illustrative of the invention and

as being one embodiment thereof. Nothing herein is to be taken as limiting the invention except as specifically set out in the annexed claims.

I claim—

1. In an envelop sealing machine, the combination with envelop separating mechanism comprising an endless belt, of envelop feeding mechanism to receive the envelop from the separating mechanism and to feed it through the machine comprising two endless belts narrower than the separating belt, and of means to the side of the feeding means for turning the flaps into the plane of the body of the envelop, the said turning means extending to a point above the belt. 70
2. In an envelop sealing machine, the combination with envelop separating mechanism comprising an endless belt, a separating roll above the forward part of the endless belt, and narrower than said belt, of means for receiving envelops from the separating mechanism, and feeding them through the machine, and means to the side of the feeding means for turning the flaps into the plane of the body thereof, the said turning means extending to a point above the belt and to the side of the separating roll. 80
3. In an envelop sealing machine, the combination with envelop separating mechanism comprising an endless belt, of envelop feeding mechanism to receive the envelops from the separating mechanism and to feed them through the machine comprising two endless belts narrower than the separating belt, and of means to the side of the feeding means for turning the flaps into the plane of the body of the envelop, the said turning means extending to a point above the belt, 90 said turning means being adjustable laterally of the feed belts to accommodate envelops of various sizes. 95
4. The combination in an envelop sealing machine of envelop holding means, means for separating envelops therefrom, one at a time, feeding means to receive said envelops and feed them through the machine, said feeding means comprising two 100 endless belts one above the other, and means located laterally of the belts and in the plane of the contacting surfaces thereof, for turning the flaps into the plane of the body of the envelops, said turning means having one edge parallel to and in close proximity to the belt, and another edge gradually approaching said first mentioned edge in the direction of the separating means. 105
